US00D962239S

(12) **United States Design Patent** (10) Patent No.: **US D962,239 S**
Arenas de Jesus et al. (45) Date of Patent: **** Aug. 30, 2022**

(54) **PEDESTAL SCANNER**

(71) Applicant: **Amazon Technologies, Inc.**, Seattle, WA (US)

(72) Inventors: **Ana Maria Arenas de Jesus**, Seattle, WA (US); **Sara Elizabeth Stille**, Seattle, WA (US); **Spencer Ralph Dodge**, Covington, WA (US)

(73) Assignee: **Amazon Technologies, Inc.**, Seattle, WA (US)

(**) Term: **15 Years**

(21) Appl. No.: **29/747,201**

(22) Filed: **Aug. 20, 2020**

(51) LOC (13) Cl. **14-02**

(52) U.S. Cl.

(57) **CLAIM**

The ornamental design for a pedestal scanner, as shown and described.

DESCRIPTION

FIG. 1 is a top, front, left-side perspective view of a pedestal scanner;

FIG. 2 is a bottom, front, right-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the pedestal scanner that form no part of the claimed design.

1 Claim, 8 Drawing Sheets
